SNOW OR WATER SKI DEVICE

Richard V. Jennings, Pickney, Mich.

Application March 27, 1948, Serial No. 17,515

1 Claim. (Cl. 280—21)

1

This invention relates to winter or water sports apparatus and, in particular, to ski devices.

One object of this invention is to provide a snow or water ski device having skis as runners which are so interconnected and provided with controlling devices that an inexperienced person can control the action of the skis with skill and precision.

Another object of the invention is to provide a snow or water ski device having skis as runners which are interconnected by a parallel link mechanism whereby the skis are maintained constantly in parallelism yet may be steered merely by the operator leaning to one side or the other.

Another object is to provide a snow or water ski device having skis as runners interconnected by a parallel link mechanism wherein the links are also provided with universal joints such that one ski may tilt longitudinally relatively to the other ski so as to facilitate traversing an uneven surface, as in going over humps or waves.

Another object is to provide a snow or water ski device of the foregoing character, wherein a handle is provided connected to one or both skis by the aid of which the operator by leaning to one side or the other may more easily tilt the skis and thereby execute turns quickly and easily.

In the drawings:

Figure 1 is a perspective view of a ski device according to a preferred form of the invention;

Figure 2 is an enlarged fragmentary side elevation of the foot supporting portion of the ski device;

Figure 3 is a side elevation, partly in section, of one end of the rear ski-connecting link; and

Figure 4 is a view, partly in section, of one end of the forward ski-connecting link.

Referring to the drawings in detail, Figure 1 shows a ski device generally designated 10, according to a preferred form of the invention, as including as runners a pair of skis 11 interconnected by a connecting and control mechanism generally designated 12. The skis 11 may be of any suitable material, such as wood, but in the drawings they are shown as made of channel metal such as channel aluminum. For use in the water they are, of course, preferably made of buoyant material. Each ski is provided with a block 13 of wood or other suitable material inserted in the channel thereof at approximately the midpoint of the ski and secured thereto in any suitable manner, as by the fasteners 14.

The connecting and control mechanism 12 is mounted upon these blocks 13, or directly upon

2

the skis 11 themselves, if the skis are made of wood. The connecting and control mechanism 12 includes a set of posts 15, 16 and 17 having base plates 18, 19 and 20 respectively fastened to each block 13, the posts 15 and 16 supporting a horizontal rod 21 and each post 17 curving into a horizontal portion 22 connected as by welding to the post 16 on a slightly lower level than the rod 21 so as to serve as a heel rest for the shoe S of the wearer. The rod 21 is provided with a transverse rod 23 serving as a toe rest for the shoe S and having retaining members 24 at the opposite ends thereof. The rod 21 is also provided with an extension rod 25 secured to the cross rod 23 and extending in a forward direction.

Secured as by welding to the forward end of each extension rod 25 is a short sleeve or bushing 26 (Figure 4) in which is journaled the stem or stub shaft 27 of a universal joint yoke 28 connected by the pivot pin 29 to a block 30 which is, in turn, connected by the pivot pin 31 to the mating universal joint yoke 32, the whole forming one of a pair of forward universal joints, each generally designated 33. A retaining collar 34 is welded or otherwise secured to the outer end of the stub shaft 27 beyond the sleeve or bushing 26. The opposite forward universal joints 33 are connected by a forward link 35 in the form of a rod which, by reason of the construction shown in Figure 4, is freely rotatable due to the mounting of the stems 21 in the bushings 26. At the same time, the universal joints 33 may rise and fall independently of one another, as the skis 11 tilt while passing over uneven ground.

Secured as by welding to the junctions of each post 16 and rod 21 is the horizontal portion 36 of a tubular control handle or lever 37, the vertical portion 38 of which terminates in a hand grip 39. Secured as by welding in the inner end bore 40 of each horizontal portion 36 (Figure 3) is the stem 41 of a universal joint yoke 42. The yoke 42 is connected by the pivot pin 43 to a block 44 which, in turn, is connected by the pivot pin 45 to the universal joint yoke 46, these parts as a whole forming one of a pair of rearward universal joints, each generally designated 47. The yoke 46 has a stem 48 loosely and rotatably mounted in a bushing or sleeve 49 and is retained therein by a washer 50, mounted upon the headed reduced diameter portion 51 thereof. The sleeve or bushing 49 is secured as by welding to a tubular link 52, the opposite end of which is similarly connected to a similar bushing 49 rotatably

supporting the stem 48 of a similar rearward universal joint 47.

In the operation of the invention, on a snowy slope the user or operator stands on the rods 22, 21, 23 as indicated by the dotted lines representing his shoes S in Figure 2, and gives a push with one foot to start himself down the slope. As he descends the slope, he steers the scooter by leaning to one side or the other, thereby shifting his weight toward the side in which the turn is to be made. Also in well-packed or crusty snow, a certain amount of turning can also be made by grasping the hand grip 39 and swinging the handles 37 to one side in the direction of the turn. This action rocks the skis 11 about their longitudinal axes, causing the turn to be made. This rocking action of the skis is permitted by the universal joints 33 and 47.

As the device descends the slope, each ski 11 may tilt relatively to the other in a lengthwise direction, as in going over humps, yet the skis will always be maintained substantially parallel to one another by the parallel links in the form of the links 35 and 52 working in conjunction with the universal joints 33 and 47 and their rotatable connections within the sleeves 26 and 49. Thus when one ski 11 starts turning, for example the right-hand ski 11 to the right, in response to the operator's leaning to the right, the other ski 11 is automatically pulled and tilted in the same direction by the connecting and control mechanism 12, including the links 35 and 52.

In this manner, the most inexperienced operator or user can control the device perfectly at all times and can steer it quickly and precisely to avoid obstacles in his path. Since the handles 37 are at the side of the operator, they are always accessible, yet not in a position where they would injure him in the event of his being pushed forward. Furthermore, unlike the case with ordinary skis, the operator is not strapped to the skis but in the event that he believes the speed or the slope is becoming dangerous and is unable to steer out of the way, he can in an emergency jump off and free himself instantly.

The connecting and control mechanism 12, including the links 35 and 52 and universal joints 33 and 47 automatically prevents the unpleasant and often dangerous experience of novices in having their skis separate outward or cross inward, since the skis of the present scooter are always maintained in substantially parallel positions. Accidents caused by the separating or crossing of the skis in ordinary skis thus cannot happen in the use of the snow scooter of this invention. The user of the present device, therefore, is enabled to experience all the thrills and satisfaction of skiing without undergoing the long rigorous and often hazardous period of training required in learning to use ordinary skis in very hilly forested country.

Another advantage of the ski device of the present invention is that by reason of the parallel link and universal joint construction of the connecting and control mechanism 12, the user on reaching the bottom of the slope can instantly fold the skis 11 alongside one another like folding a parallel ruler, such as is used in navigation. When the device is folded in this manner, the user can throw it over his shoulder or onto an automobile or ski tow and walk or ride either

to the top of the slope or elsewhere, as he may desire.

When the ski device of this invention is used on the water, the skis or runners 11 will be broader and, if desired, longer than those used for snow. They will also preferably be of wood so as to float when the device is at rest. In water skiing with this device, the tow line to the motor boat may be grasped directly by the operator or attached to the cross member 52 or 35, or connected by a V-shaped bridle to the supporting structures mounted on the blocks 13, such as to the members 26, or attached to a harness around the body with a quick release connection. The handles 37, 39 in the water ski device are used in a similar manner as on snow, and in a similar way, the operator may lean to one side or the other in executing turns.

As in snow, the turn is brought about mainly by the action of the upwardly curved forward ends of the skis or runners 11 which, when tilted sidewise, serve to direct the skis toward the side to which they are turned. The individual tilting action of the skis when used in water is also useful when a wave will tilt one ski more than the other, the universal joints permitting such tilting yet retaining the parallel relationship of the skis. In the event that the operator loses his balance, or for any other reason desires to free himself from the device, he can jump to one side or the other or drop backward into the space between the skis at an instant's notice since he is not strapped to the device.

What I claim is:

35 A ski device, comprising a pair of laterally-spaced elongated runners arranged substantially parallel to one another, a foot supporting structure mounted on each runner, a pair of spaced substantially parallel links connected to and extending between said runners, pivotal connecting devices arranged between said links and said runners, said pivotal connecting devices having universal joints with rotatable couplings connected between said runners and said links, said universal joints being constructed and arranged to effect free individual rocking of said runners relatively to one another in all directions, and a pair of control members having bent lower ends connected to and extending upward respectively from 40 said supporting structures substantially to the hand level of an operator standing upon said supporting structures.
